Byron M. Schmuhl, Centerline, Mich.

Application December 7, 1936, Serial No. 66,371

Term of patent 7 years

To all whom it may concern:

Be it known that I, Byron M. Schmuhl, a citizen of the United States, residing at Centerline, in the county of Macomb and State of Michigan, have invented a new, original, and ornamental Design for a Combined Spout and Closure for Containers, of which the following is a specification, reference being had to the accompanying drawing, forming a part hereof, in which,

Figure 1 is a plan view of a combined spout

and closure for containers showing my new design.

Figure 2 is a front elevational view of the same.

Figure 3 is a side elevational view of the same.

Figure 4 is a rear elevational view of the same, and

Figure 5 is an underside view.

I claim:

The ornamental design for a combined spout and closure for containers.

BYRON M. SCHMUHL.
